UNITED STATES PATENT OFFICE.

ISABEL LIKENS GATES, OF WASHINGTON, DISTRICT OF COLUMBIA.

GARMENT SUPPORT.

Application filed August 24, 1922. Serial No. 584,020.

To all whom it may concern:

Be it known that I, ISABEL LIKENS GATES, a citizen of the United States, residing at Washington, District of Columbia, have invented certain new and useful Improvements 5 in Garment Supports, of which the following is a specification.

The invention relates to camisoles or similar articles of lingerie which are supported 10 or hung from the shoulders of the wearer, and more particularly to the provision of means for supporting a garment of this character in such manner as to obviate the tendency of such supporting means to slide 15 off from the shoulders of the wearer.

A further object of the invention is the provision of a supporting means comprising a strap or ribbon formed from a single piece, and which can be very readily applied 20 or removed when the garment is to be laundered, and which will be attractive in appearance.

Illustrative embodiments of the invention are shown in the accompanying drawing, in 25 which

Fig. 1 is a perspective view of the garment and its supporting means in place;

Figs. 2 and 3 are plan views of two forms 30 of the invention with the garment omitted. As shown in Figs. 1 and 2, the device comprises a strap or ribbon having its portions near its ends, as 10—11, run or threaded through the front upper edge of the garment 12, after which portions 13—14 extend 35 upwardly to the shoulders.

At the shoulders the portions 13—14 are looped over each other, 15—16, and continued downwardly at 17—18, to a point adjacent the arm pit of the wearer. From here 40 the ribbon is threaded or run through the upper edge of the garment again, thence under the arm, as at 19—20, to a point behind the arm pit.

The strap or ribbon beyond the portions 45 19—20 then again leaves the garment and passes up to the shoulder, as at 21—22, Fig. 2, where the loops 38—39 are formed, with which the loops 15—16 engage.

Beyond the loops 38—39 the strap or ribbon 50 is again run downwardly, as at 23—24, and then forms the horizontal portion 25, which is run or threaded through the upper edge of the goods of the garment at the back in the same manner as already described for 55 portions 10—11.

While the strap or ribbon is described as being threaded through the edge of the garment, shown as a net-like border in the figure, it will be understood that any desirable manner of running the strap, which will 60 make the same readily removable, may be utilized. The ends 26—27 may be tied in a bow 28, as plainly shown in Fig. 1.

In the form of the invention shown in Fig. 3, the parts 10 and 11 instead of passing through loops at the shoulder, form the parts 29—30 which run completely over the shoulder in a diagonal direction to a portion directly in the rear of the arm pit of the wearer. The portions 31—32 are run through 70 the goods of the garment to a position closely adjacent the forward portion of the arm pit when they emerge from the goods and, as portions 33—34 are extended over the shoulder in a diagonal direction, crossing the parts 29—30 and forming the portion 35 at 75 the back of the garment, which portion is run through the goods of the garment. The ends 36—37 of this form of the device may also be tied in a bow. 80

It is found that a strap formed of ribbon and run as described is very comfortable to wear and has no tendency to slip down off the shoulders, thus relieving the wearer of the necessity of awkward, and sometimes 85 embarrassing movements required to replace the ordinary form of suspension means in position.

A further advantage of this improved garment support consists in the fact that it 90 avoids the tearing of the garment to which it is attached, due in some measure to the greater area of contact therewith, and the further fact that it yields with the movements of the wearer, thus avoiding strain on 95 any particular portion of such garment.

Minor changes may be made in the physical embodiment of the invention without departing from its spirit. 100

I claim:

1. In combination with a garment, a support comprising a front strap section and a rear strap section, each section comprising an inverted V shaped strap portion with the apices of the V shaped portions interlooped 105 and the arms of the V shaped portions attached to the garment.

2. In combination with a garment, a support, comprising a strap engaging the garment through a portion of the front thereof 110

and a portion of the back thereof, extending from such engaged portions diagonally upwardly and outwardly from front and back to the top of the shoulder of the wearer, 5 thence downwardly and outwardly from the top of the shoulder to points adjacent the front and rear of the arm pit, and engaging the garment under the arm pit.

3. In combination with a garment, a support 10 port comprising a ribbon engaging the garment through a portion of the front thereof

and a portion of the back thereof, extending from such engaged portions diagonally upwardly and outwardly from front and back to the top of the shoulder of the wearer, the 15 portions from front and back looped through each other, thence extending downwardly and outwardly to points adjacent the front and back of the arm pit of the wearer, and engaging the garment under the arm pit.

ISABEL LIKENS GATES.
